UNITED STATES PATENT OFFICE.

STANLEY ANTHONY, OF BOSTON, MASSACHUSETTS.

CARD-INDEX.

1,330,510.

Specification of Letters Patent.

Patented Feb. 10, 1920.

Application filed March 25, 1919. Serial No. 284,903.

To all whom it may concern:

Be it known that I, STANLEY ANTHONY, a citizen of the United States, residing at Boston, county of Suffolk, State of Massachusetts, have invented an Improvement in Card-Indexes, of which the following description, in connection with the accompanying drawing, is a specification, like characters on the drawing representing like parts.

10 This invention relates to card indexes of that type which comprise a frame, a plurality of card holders or card carriers removably sustained in said frame one above the other and index cards pivotally connected 15 to the carriers and arranged in overlapping relation so that the bottom of each card projects below the bottom of the next card above.

When card indexes of this type are being 20 used, it is necessary to remove individual cards from the card carrier in order to add thereto some desired data, and in many cases it is desirable to add the data on the card through the typewriter as an instrumentality. To do this the individual cards must be so constructed that they can be 25 readily inserted into and run through a typewriter. In my prior application for United States Letters Patent Se. No. 30 114,674, filed August 14, 1916, I have shown a card index in which the cards are pivotally secured to the card carriers or holders by means of metallic hinge members which are detachably secured to the card holder or 35 carrier and which are also constructed so that they can be removed from the card. Where metallic hinge members of this type are used, the operation of typewriting on any individual card involves first the step 40 of detaching the hinge members from the carrier and then removing the hinge members from the card.

By my present invention I have provided an improved form of card and card carrier 45 which is constructed so that the card can be removed from the hinge members without removing the hinge members from the carrier and while the carrier is still in the frame so that the operation of adding any data to 50 an index card on the typewriter involves simply removing the card from its hinge members.

The frame which is used in a card index of this type is provided with a back having 55 retaining lips at its edges under which the ends of the card carriers are received. In

some indexes, these lips are made of sufficient depth so that they can be used to receive index members in the form of strips of paper incased in celluloid sheaths. 60 Where index members of this character are used, it is necessary to make the lips of a greater width than would be required for receiving the metallic card carriers illustrated herein. Where the frame is provided 65 with the wide retaining lips, it has been customary heretofore to make the metal carriers of sufficient length so that they extend the full width of each lip, the purpose of this being to prevent the carriers from moving 70 in the direction of their length after they have been inserted in the frame. Where the carriers do thus extend the full width of the relatively wide lip, some difficulty is involved in removing them because 75 in bending them outwardly to shorten their length they are apt to bind against the lip.

I have provided herein a novel form of carrier which is adapted to be used with a frame having a relatively wide lip, but 80 which is constructed so that it extends only part way beneath the lip and yet is held from longitudinal movement. A carrier involving my improved construction can be very readily removed and when it is in place 85 it is securely held against movement.

In order to give an understanding of my invention, I have illustrated in the drawings some selected embodiments thereof which will now be described, after which the 90 novel features will be pointed out in the appended claims.

Figure 1 is a perspective view of a card index embodying my invention;

Fig. 2 is a perspective view of a carrier 95 with its hinges, a part being broken away;

Fig. 3 is a fragmentary view of a portion of a card adapted to be attached to said hinges;

Fig. 4 is an enlarged section on the line 100 4—4, Fig. 2;

Fig. 5 is an enlarged section on the line 5—5, Fig. 1;

Fig. 6 is a fragmentary view showing a different embodiment of my invention; 105

Fig. 7 is a view of a card adapted to be used with the hinge shown in Fig. 6;

Fig. 8 is a view showing a still different embodiment of the invention;

Fig. 9 is a fragmentary view of a card 110 adapted to be used with the hinge shown in Fig. 8.

1 indicates a frame, 2 the holders or card carriers which are removably sustained in the frame and 3 the index cards. The card holders or card carriers herein shown are in 5 the form of resilient strips of metal which have their ends confined beneath the lips 4 of the frame. Each carrier has two hinge members 5 pivotally connected thereto, these members preferably being of metal and having the eyes 6 which embrace the pintles 7 that are struck up from the holder 2.

Each card 3 is constructed to detachably engage the hinge members 5 to which it is attached, the construction being such that 15 each card can be readily removed from its supporting hinge members without removing the corresponding card holder from the frame. Various constructions might be employed that would permit of this operation, 20 and in the drawings I have illustrated some which will demonstrate the principle of the invention. In the construction shown in Figs. 1 to 4, each hinge member is provided with a card-retaining projection formed at 25 its ends with laterally-extending lips, and the card is provided with a slot to receive such projection, the lips of the projection overlapping the edge of the slot and thus retaining the card in position. This projection 30 may be formed in various ways. One simple way is to strike it up from the hinge member, and in the drawings the hinge member has the two arms 7 struck up therefrom, the end of each of which is bent laterally, as shown at 8, to form a retaining 35 lip. The two arms together form a projection adapted to occupy the slot of the card, and the lips 8 overlie the edge of the slot. The slot in the card which receives the projection is indicated at 9 and the two slots 9 40 for each card extend in opposite directions and are so relatively situated that when the card is in place on the hinge members the two projections occupy the inner ends of 45 the slots. The lips 8 overlie the edges of the slots and prevent the cards from being pulled off from the projection. The outer end of the slots 9 may extend to the edge of the card or may open into enlarged apertures 10, as desired. In Fig. 3 I have shown 50 them as opening into apertures 10 which are of a size to permit the projections with their lips to pass therethrough. In Fig. 7 I have shown them as extending to the edge of the card.

In attaching a card of the type shown in Fig. 3 to the hinge members, one of the openings 10 will be placed over a projection on one of the hinges and then the card will be 60 shifted endwise to cause said projection to enter the slot 9. The card may then be bent to shorten its length sufficiently to permit the other projection to pass through the other aperture 10 and then when the card is 65 allowed to assume its natural position, said

other projection will enter the other slot 9, thus locking the card in place. A reversal of these operations will result in detaching the card from the hinge members. The card can thus be attached to or removed from the 70 hinge members of any card carrier without removing the card carrier from the frame, and when the card is removed it has no projections thereon which interfere at all with its being inserted into and passed through 75 the typewriter.

In Fig. 6 I have shown a hinge member having a slightly different construction, said member being formed with the eye or loop 11 through which a projection 12 on the card 80 3 may be inserted. This projection can conveniently be made by forming a slot 14 in the edge of the card and the card will be attached to the hinge, as shown in Fig. 6. This same card can be used with the hinge member shown in Figs. 1 to 4, as above described. In Fig. 8 I have shown a different embodiment of the invention wherein each hinge member 5 is formed with a laterally-extending arm 15, the end of which is bent transversely of the hinge member, as shown at 16. This embodiment is adapted to be used with a card having either the slot 14 of Figs. 6 85 and 7 or a card with the opening 10 and slot 9 shown in Fig. 3, or with simply an opening 17, as shown in Figs. 8 and 9.

The lips 4 herein shown are relatively wide so that the frame 1 can be used with the type of index member which is in the form of a narrow strip of paper incased in 100 a transparent sheath.

In order to retain the metallic holders 2 in place, it is not necessary that the ends thereof should extend the full width of the lips 4, but if they are made shorter then the 105 holders will be permitted to have an endwise movement which is undesirable. In order to prevent this I propose to form each holder 2 with a positioning projection 18 at each end, said projections being situated 110 to engage the edges 19 of the lips 4 when the holders or carriers are in place. These positioning projections 18 prevent the holders or carriers from longitudinal movement and thus make it possible to use a holder 115 which is of such a length that the ends thereof will extend only part way across the lips, as shown in Fig. 5. Where the holder extends under the lips for only a short distance, said holder can be readily removed 120 from the frame or replaced therein without producing any binding action such as would occur if the end of the holder extended the full depth of the lip.

I claim:

1. In a card index, the combination with a frame, of a plurality of card carriers sustained thereby, each having a pair of hinge members pivotally connected thereto, and an index card detachably sustained by each 130

pair of hinge members, each card being removable from its hinge members without removing the carrier from the frame.

2. In a card index, the combination with 5 a frame having a back and retaining lips at its edges, of a card carrier having its ends inserted under said lips and retained in position thereby, said card carrier having positioning projections which engage the edges 10 of the lips and thus prevent longitudinal movement of the carrier, and an index card sustained by said carrier.

3. In a card index, the combination with a frame, of a plurality of card carriers sus-

tained thereby, each having a pair of hinge 15 members permanently pivoted thereto, and a card carried by each pair of hinge members, each card being removable from its hinge members without removing the carrier from the frame.

4. A holder or carrier for cards of a card index system, said holder being made of a strip of metal and having card-supporting 20 hinges permanently pivoted thereto.

In testimony whereof, I have signed my 25 name to this specification.

STANLEY ANTHONY.
